R. H. THORNTON

STREAM IMPROVEMENT

Filed Nov. 23, 1922

Inventor:
Richard H Thornton

J. Greinke
Atty

UNITED STATES PATENT OFFICE.

RICHARD H. THORNTON, OF PORTLAND, OREGON.

STREAM IMPROVEMENT.

Application filed November 23, 1922. Serial No. 602,786.

To all whom it may concern:

Be it known that I, RICHARD H. THORNTON, a citizen of the United States, and a resident of Portland, county of Multnomah, 5 and State of Oregon, have invented a new and useful Improvement in Stream Improvement, of which the following is a specification.

As well known, if the natural channel of 10 a river is narrowed by an abutment placed in one side thereof the flowing waters will secure the necessary cross sectional area by increasing the depth until the area lost by the decreased width is regained by the increased depth and equilibrium is again 15 restored. It is also well known that the waters flowing over the shallow part of a stream are subjected to much greater friction by the river bottom than the deeper 20 parts, and therefore will flow with diminished velocity.

J. L. Van Ornum in his book entitled "The Regulations of River" (Washington University 1914) states:

25 "If in one part of (a river) the velocity of the stream is great enough to scour the bed, and the water becomes loaded with silt, and in (another) part of the river's course the velocity is diminished, then part of the 30 transported material must be deposited. Probably deposit and scour go on simultaneously over the whole river bed; but in some parts the rate of scour is in excess of the rate of deposit, and in other parts the 35 rate of deposit is in excess of the rate of scour."

The object of my invention is to direct 40 these physical properties of nature so as to cause scouring in one part, and deposit in another part of the stream. My further object is to produce such result at a low cost.

I attain my object by building near one 45 shore of the stream a wall or abutment inclined at an angle up stream, with one end projecting into one side of the channel, and the other end extending to a convenient point in the shallow waters.

The flow diverted towards the shallow 50 portion of the stream must not be arrested entirely, as it would be by a jetty and thus a region of back water would be created; but must be permitted to proceed on its course.

Furthermore, the wall is so designed as to 55 divide that portion of the current which impacts against it, diverting such portion

partly back into the channel, and partly into the shallow waters along the same side of the shore. In this way, since the waters flowing over the shallow part of the stream along said shore are subjected to a much greater friction by the bottom of the stream than the deeper parts, the waters of the current, in following the line of least resistance, will tend to pass for the greater 65 part in front of the wall back into the channel and thus scour the bed; while, at the same time a portion of the silt carried in suspension by the waters passing over said shallow portion will be deposited and after 70 a time form a solid embankment.

In order to promote said result that end of my wall projecting into the channel is curved back upon itself in the form of a hook presenting a curved surface for a two 75 fold purpose: first, to provide a space enclosed by said wall, in which silt may be collected and by so doing causing an island-like formation adding to the solidity of the wall structure, which besides may be used 80 for other purposes; secondly, the curved back wall tends to produce a swirl around said hook and to fill in said enclosed space by deposits.

Other features of my invention and the 85 mode of practicing the same are hereinafter fully described and diagrammatically illustrated in the accompanying drawings, in which:

Fig. 1 shows a plan of a river with my 90 means for utilizing the current of the channel to scour out the latter, diagrammatically shown; and

Fig. 2 shows a modification which may be made in the construction of the wall, *e*, *g*, *h*, 95 shown in Fig. 1.

I carry my invention into practice as follows: First, I plat a straight line *a*, *b*, from the point *a*, approximately transversely to the course of the main channel of the river opposite to that point. Next I plat a straight line *c*, *a*, *d*, at or near the shore, and at right angles to the line *a*, *b*. Then I bisect the right angle, *a*, *b*, *d*, which is assumed to face upstream; the flow of the river being indicated by the arrows. I then build a wall along the said bisecting line, which in the drawings is indicated by the broken line *f*. Said wall may deviate a few degrees on either side of said bisecting line, with the angle measured from *a* as a center. The angle at which the wall so built may deviate

from said line of bisection *f* is to be determined by the engineer in charge of the work, according to the contour and velocity of the current. This wall should begin at a point *e* in said line of bisection *f*, said point *e* being located in the shallow water along the adjacent or left bank, and not very far from the edge of the current. The wall is projected into one side of the channel of the river, and at the extremity of such projection it is curved inward, or in other words the projecting wall portion is bent back on itself, towards the bank on the same side of the river. The construction of this wall is grammatically represented in the drawing 18 by the heavy line *e, g, h*. The form of said curve may be semicircular or elliptical, but the wall portion included in the long arm section *e, g*, must be substantially longer 20 than the portion *g, h*.

The theory of the effect produced by my wall may be said to be as follows with reference to the drawings: Since the wall portion at *g* projects into the channel of the river, the waters of the channel striking 25 against the wall portion *g, h*, will tend to deflect towards the left bank, and thus produce a side current or swirl which would tend to carry the silt and other matter suspended in these waters along the wall portion *g, h*, and the latter will tend to cause 30 the deposit of such matter in the shallow water along said bank. The swirl occasioned around the point *h* of the wall portion *g, h*, would further tend to fill the space 35 enclosed by the wall *e, g, h*, with deposits from said material, and in that way strengthen this wall by forming a solid abutment. The passage of the water as 40 diverted, however, is not restrained, but is permitted to flow on along the left bank of the river, and thru the opening left between the point *e* constituting the near end of said wall, and the point *a* on the adjacent shore; 45 for if the opening between *e* and *a* were closed a back water would result which would frustrate the purpose and function of the wall *e, g, h*.

In order to promote the arresting and deflection of the silt and other material suspended in the water of the channel as mentioned, the wall portion *e, g*, may be provided with an angular projection or beak *i*. This need not be of a permanent character, 50 for in my opinion, if it lasts until the space

enclosed by the wall *e, g, h* is filled up to a reasonable extent, said extension will have served its purpose.

The diversion of part of the material carried in suspension by the current will 60 prevent its deposit in the channel, and thus tend to keep the latter clear down the river beyond the wall. The described wall may of course be built on either side of the river; and if it be built on the right side, the words 65 "right bank" are to be understood as substituted for "left bank" in this description. Hence by means of said wall the current in the river will be utilized to gradually scour out its own channel for a considerable distance. 70

The construction of the wall must be planned so that said scouring action will not tend to change the channel of the river, unless that result be desired. 75

The material of which the wall *e, g, h*, is built must depend upon the circumstances. For example it may be made of piling or it may be built in any other way now practiced in similar wall construction. 80

The particular utility of applicant's invention lies in the low cost of the improvement of the river. The only material which will have to be brought in from an outside source is that which goes into the construction of the wall. When this has been built an island will be formed by the deposits within the hook, and the island will reinforce the wall and greatly strengthen it; also the silt deposited in the shallow water 85 supplements the land along the shore. In this way dykes or levees may be formed along a bank, or an island or islands formed in the stream, which may be connected or otherwise caused to subserve the necessities 90 or conveniences of life; for instance facilitate the construction of a boom for confining logs. 95

I claim:

Means for directing the current of a 100 stream so as to make land-forming deposits of its silt, said means consisting of a wall built at an acute angle up stream from a point located in the shallow waters off one shore to a point located in the same side 105 of the channel of the river, such wall composed of a long straight arm terminating at that end projecting into the channel in a short arm curved back upon itself.

RICHARD H. THORNTON.
